PACKING FOR COLLAPSIBLE TUBES

Henry R. Kohlhepp, Saginaw, Mich., assignor to
 American Box Board Company, Grand Rapids,
 Mich., a corporation of Michigan

Application June 25, 1945, Serial No. 601,419

4 Claims. (Cl. 229—87)

The present invention relates to a packing or a container for collapsible tubes, made from paper and of particular utility in protecting the tube in shipment or storage.

It is a primary object and purpose of the present invention to provide a packing for collapsible tubes, which may hold many varieties of liquid or semi-liquid material and which are dispensed by collapsing the side of the tube and forcing the material out of an end opening thereof. With my invention the container is made from a single substantially rectangular sheet of relatively thin paper stock, which when properly scored and slotted and cut at its outer edges provides an enclosing holder or packing for the collapsible tube, very little waste of material occurring in slotting and cutting the blanks. Said packing when applied to the tube is adapted to be placed within a shipping container of paper or paper board of suitable rectangular dimensions in cross section, the tube with the packing around it being readily received therein.

An understanding of the invention may be had from the following description taken in connection with the accompanying drawing, in which,

Fig. 1 is a plan of blank from which the collapsible tube packing is made.

Fig. 2 is a perspective view showing one-half of the blank in its completed shape, the other not yet having been folded, and

Fig. 3 is a somewhat enlarged end elevation showing a collapsible tube within the completed packing of my invention.

Like reference characters refer to like parts in the different figures of the drawing.

The blank of suitable paper stock of the requisite thickness, and of generally rectangular form, at its center longitudinally thereof has two aligned rectangular sections 1, integrally connected at their inner ends and scored or otherwise processed for bending transversely at said meeting ends on the line 2. Outwardly the blank is slotted to each side edge, providing two narrow slots 3, one extending from each end of the line of bending 2 shown.

The rectangular sections 1 at their side edges are defined by parallel spaced longitudinal scored or bending lines 4, at the outer side of each of which is a triangular section 5, widest at its outer end and progressively decreasing in size to a point which points reach substantially the inner ends of the slots 3. The outer boundary of the section 5 is provided by a scored or bending line 6 located at an acute angle to its adjacent line 4 as shown. Parallel to each of the lines 6 is a scored or

10 bending line 7, reaching from each end of the blank and each side of the intermediate sections 1 and 5 to the slots 3, thereby providing substantially rectangular sections 8. Outward from the 15 scored or bending line 7 are substantially rectangular sections 9. The outer longitudinal edges of the section 9 parallel the bending line 7, and the outer end edges of the sections 8 and 9 are perpendicular to the bending lines 6 and 7 as shown.

10 In the use of the packing, the two sections 9 at one side of the slots 3 are bent at right angles to the adjacent sections 8 about the lines 7, and the sections 8 are bent at right angles to the 15 triangular sections 5 bringing the two sections 9 into overlapping relation with respect to each other as in Fig. 2. Said sections 9 in such overlapped relation and brought with their outer edges in parallelism to the bending lines 7 form 20 one-half of a packing, in which the center section 1 is pressed downwardly and formed into a concave trough 1a (Fig. 2) between the tapered upper portions 5. It is apparent that the recessed portion 1a, provided by the downwardly concaved 25 shaping of the section 1, progressively decreases as to its depth from the outer free end toward the inner end where it is connected at the bending line 2 to the aligned section 1a of the other half of the packing. The collapsible tube 10 may be placed within the trough-like recess indicated at 30 1a with its closed end adjacent the transverse scored or bending line 2. The other half of the packing may be bent on the lines 4, 6 and 7 into a like formation and then turned approximately 35 180° about the transverse line 2 so as to enclose the body of the collapsible tube 10, with only the delivery end of the tube exposed, as shown in Fig. 3.

40 The packing thus supplied to the tube is designed to be located in a container of the proper dimensions in length and rectangular in cross section.

45 The construction described is simple, is economical to make with minimum loss of material, and provides a very satisfactory protection and an insurance against damage to the thin-wall flexible tubes which it is designed to receive.

50 The invention is defined in the appended claims and is to be considered comprehensive of all forms of structure coming within their scope.

I claim:

1. In a device of the class described, a two part container of thin material including, two intermediate aligned elongated sections, one foldable over the other, each of said sections at its

outer end being of concaved shape and progressively decreasing in depth from its outer to its inner end, triangular sections extending outwardly one from each edge of said intermediate sections, side sections extending at right angles from said triangular sections, and overlapping edge sections located at right angles to said side sections, whereby when one of the intermediate sections is turned about the meeting juncture of said two intermediate sections a recess for receiving a collapsible tube is provided, one-half of said recess being in each of the two parts of the container.

2. A blank for a packing for flexible tube containers, formed of thin material having a generally rectangular outline, said blank midway between its ends having transverse aligned slots one from each side edge extending inwardly for a distance, said blank having bending lines lengthwise thereof at the inner ends of said slots, said blank also having a bending line between the inner ends of said slots, other bending lines disposed one at an acute angle to each of the first longitudinal bending lines extending outwardly from the ends of said slots, and additional bending lines one parallel to each of the last mentioned bending lines, said material of the blank being bendable about said various lines to form an enclosing packing open at one end for the reception of said collapsible tube container.

3. A container for a collapsible tube comprising, upper and lower parts integrally connected at one end and foldable one over the other, each of said parts having two outer overlapping sections to form the bottom and top of the container, vertical sections extending at right angles from said overlapping sections toward each other, inwardly turned horizontal sections of triangular form in contact engagement with each other and intermediate trough-like sections disposed in opposition to each other, the depth of said last mentioned sections being greatest at their outer ends and becoming progressively wider and shallower toward their inner ends.

4. A packing container for a flexible collapsible tube comprising, upper and lower members made of paper material, one superimposed over the other and having longitudinal trough-like recesses shaped to receive said tube therein, each of said members having walls of triangular form continued one outwardly from each edge of said trough-like recesses for a short distance, then extend for a short distance at right angles into sides, and then bent at right angles outside of its associated trough-like recess and overlapping each other, said intermediate trough-like portions of said parts having an integral connection at their inner ends and bendable transversely at said inner ends to located one over the other.

HENRY R. KOHLHEPP.
